UNITED STATES PATENT OFFICE.

CHARLES F. HUNTOON, OF CHICAGO, ILLINOIS.

TRUCK-BOLSTER.

1,269,817.

Specification of Letters Patent. Patented June 18, 1918.

Application filed September 8, 1917. Serial No. 190,365.

To all whom it may concern:

Be it known that I, CHARLES F. HUNTOON, a citizen of the United States of America, and a resident of Chicago, county 5 of Cook, and State of Illinois, have invented certain new and useful Improvements in Truck-Bolsters, of which the following is a specification.

This invention relates to improvements in 10 truck bolsters of the type described in Patent No. 1,210,478, granted January 2, 1917.

The objects of the invention are to provide improvements in truck bolsters enabling quicker and more convenient assembly thereof; to provide an arrangement of the bolster permitting replacement or removal of the king-post or truss block for 15 repairs without disturbing the end connections of the main truss members; and to 20 provide means for at any time increasing the rigidity of the bolster, if any play or looseness should develop therein during its use.

An illustrative embodiment of the invention 25 is shown in the accompanying drawings, in which—

Figure 1 is a side elevation of the improved truck bolster, one-half of the same being shown in section.

Fig. 2 is a fragmentary plan view of the bolster.

Fig. 3 is a sectional detail taken on the line 3—3 of Fig. 1.

Fig. 4 is a perspective view of one of the 35 tightening blocks or wedges.

The invention comprises mainly the incorporation of an inclined block or blocks between the strut of the bolster and, preferably, the tension member, so that the strut 40 may be freely inserted in the bolster before the inclined blocks or wedges are applied, and then the latter may be forced in place, making the entire structure rigid and under some tension.

The drawings show a truck bolster which 45 as described in the patent mentioned herein comprises a compression member 1, in the form of a channel bar having a horizontally disposed web 2 and depending marginal flanges 3, and provided at its medial part 50 with a center bearing 4 and near each end thereof with side bearings 5.

A flat strap-like tension member 6, having its medial portion held in spaced relation to the compression member 1 by a truss block or strut 7, is bent at such medial part

so that its end portions meet the respective end portions of the web 2 of the compression member 1. The members have their ends secured together by suitable means 60 such as rivets 8, and the end portions of the compression member 1 are bent upward in the general direction of the end portions of the tension member 6 which are in alignment with their adjacent body portions. 65

The end portions of the tension member are upset or otherwise thickened so that there is no reduction of area on account of the rivet holes, and the extreme ends of the tension member 6 are provided with up- 70 standing and laterally extending shoulders 9 adapted to overlap and abut against the ends of the web and flanges of the compression member 1.

Means are provided for strengthening 75 and reinforcing the shoulders 9 and comprise ribs 10 disposed longitudinally of and on the upper surface of the tension member 6, the web of the compression member being recessed to receive these ribs. 80

The present improvements relate to the specific structure of the strut or truss block 7 and the wedge blocks 11. The base of the truss block 7 is inclined inwardly and downwardly from its sides to its center, as shown 85 in Fig. 3, thus providing inclined surfaces 13 for coöperating with the inclined surfaces 12 of the wedge blocks 11. Before the wedge blocks are inserted in the structure, considerable space is provided between the base of 90 the truss block and the tension member 6. Accordingly, after the tension and compression members are riveted together at their ends, the strut 7 may be without difficulty inserted between the tension and compression members and secured to the latter. 95 Finally, the blocks 11 are placed in the structure and either by riveting or by means of a bolt 14 are drawn together and wedged between the inclined base of the strut 7 and the upper surface of the tension member 6. The strut and the wedge blocks 11 are preferably so proportioned that after the assembly of the structure, there is little or no space between the inner ends of the wedge 105 blocks.

If, after considerable use of the bolster, play should develop in the structure, the wedge blocks may be utilized to take up such play, either by forcing the blocks toward 110 each other, or replacing the blocks with new ones. As shown in the drawings, the wedge

blocks 11 are provided with an upstanding flange on three sides thereof for the purpose of surrounding the truss member and preventing lateral displacement of the blocks.

- 5 It may be seen from the foregoing that the invention enables a reduction in the time required for assembling truck bolsters, since it is unnecessary to force apart the compression and tension members in order to insert 10 the truss member, and likewise, means are afforded for imparting the desired rigidity to the entire bolster.

Although but one specific embodiment of this invention has been herein shown and 15 described, it will be understood that numerous details of the construction shown may be altered or omitted without departing from the spirit of the invention as defined by the following claims.

20 I claim:

1. A bolster for railway cars, comprising compression and tension members secured together at their ends, a truss block between said members, said truss block being formed 25 to be removable from between the compression and tension members without disturbing the end connections between said members, and a wedge block inserted between one end of the truss block and the tension 30 member.

2. A bolster for railway cars, comprising a tension member, a compression member, said tension and compression members being secured together at their ends, a truss block

located between said members, said truss 35 block being formed to be removable from between the tension and compression members without disturbing the end connections between said members, one end of said truss block being inclined, and a wedge-shaped 40 block located between said inclined end of the truss block and one of said members.

3. A bolster for railway cars, comprising a tension member, a compression member, said members being secured together at their 45 ends, a truss block located between said members, said truss block being formed to be removable from between said members without disturbing their end connections, one end of said truss block being inclined, a wedge-shaped block located between inclined end of the truss block and one of said members, and means for retaining said block 50 snugly against the inclined surface of the truss block.

4. A bolster for railway cars, comprising tension and compression members secured together at their ends, a truss block centrally located between said tension and compression members, one end of said truss 60 block being inclined inwardly from its sides and a pair of wedge blocks being located between the inclined surfaces of said truss block and one of said members.

Signed at Chicago this 4th day of Sept., 65 1917.

CHARLES F. HUNTOON.
